UNITED STATES PATENT OFFICE.

MARY T. MORRELL, OF SYRACUSE, NEW YORK.

DESIGN FOR A BELT-HOOK.

SPECIFICATION forming part of Design No. 28,347, dated March 8, 1898.

Application filed November 20, 1897. Serial No. 659,340. Term of patent 7 years.

To all whom it may concern:

Be it known that I, MARY T. MORRELL, of Syracuse, in the county of Onondaga, in the State of New York, have invented new and 5 useful Improvements in a Design for Belt-Hooks, of which the following, taken in connection with the accompanying drawings, is a full, clear, and exact description.

Figure 1 is an isometrical elevation of the 10 hook complete detached. Fig. 2 is an edge view thereof, these two views being deemed sufficient to fully illustrate my design.

As shown in the drawings, the leading or 15 material feature of my design consists in a belt-fastener having two hooks extending in the same vertical direction upon opposite sides of a body formed by doubling a piece of sheet metal upon itself, the said body ter-

minating in said hooks, as shown, the eye 20 being formed at the central point by doubling the strip of sheet metal, the whole forming a unitary design.

a' is the strip of sheet metal, bent at *d*, forming the eye *c*, said strip terminating in hooks *a* and *b*.

Having described my invention, what I 25 claim, and desire to secure by Letters Patent, is—

The design for a belt-hook, substantially as herein described and shown.

In witness whereof I have hereunto set my hand this 14th day of October, 1897.

MARY T. MORRELL.

In presence of—

HOWARD P. DENISON,
MARY A. FRANKLIN.
